UNITED STATES PATENT OFFICE.

ANNA S. TAYLOR, OF NEW YORK, N. Y.

CLOTHES-STICK.

1,156,112.

Specification of Letters Patent.

Patented Oct. 12, 1915.

Application filed February 16, 1915. Serial No. 8,512.

To all whom it may concern:

Be it known that I, ANNA S. TAYLOR, a citizen of the United States, and a resident of the city of New York, borough of Manhattan, in the county and State of New York, have invented a new and Improved Clothes-Stick, of which the following is a full, clear, and exact description.

The invention relates to laundry appliances, and its object is to provide a new and improved clothes stick more especially designed for safely handling clothes especially lace and other delicate garments, when placing the same into a wash boiler or tub or removing the same therefrom, and to allow of conveniently supplying the wash water with a washing compound such as bluing, shaved soap, washing soda, washing powder or the like.

20 In order to accomplish the desired result, use is made of a perforate egg or bulb-shaped receptacle held on the end of a stick and provided with a separable section to allow of filling the receptacle with a washing compound, the latter dissolving on placing the receptacle into the wash water, the latter passing through the perforations in the receptacle into the interior thereof to dissolve the compound contained therein.

25 30 A practical embodiment of the invention is represented in the accompanying drawing forming a part of this specification, in which the figure is a sectional side elevation of the clothes stick.

35 40 45 50 One end of the stick A is provided with a screw thread A' screwing into the threaded neck B' of a receptacle B, preferably made egg or bulb shape and provided with perforations B², as plainly indicated in the drawing. The receptacle B is provided at the outer end with a screw cap B³ which when removed permits of conveniently filling the receptacle B with a washing compound C such as bluing, shaved soap, washing soda, washing powder or the like. After the receptacle is filled the cap B³ is again screwed in position to close the receptacle. The cap B³ fits snugly onto the mouth of the receptacle B so that the outer surface of the receptacle and its cap do not pre-

sent any projections whatever to prevent lace or other delicate garments from being injured when using the stick in placing the garments or clothes into a wash boiler or tub or removing the same therefrom, or when stirring the clothes around in the boiler or tub. It will be noticed that the user of the clothes stick can fill the same with a washing compound and then submerge the receptacle in the wash water to 55 allow the latter to pass through the perforations into the interior of the receptacle to dissolve the washing compound and to allow the solution to pass into the boiler or tub.

It will be noticed that by the use of the 60 device a desired pounding action can be given to the clothes as the wash water can readily surge through the receptacle B on moving it up and down in the boiler or tub.

If desired, the cap B³ can be omitted and 65 the receptacle made with an outer surface of unbroken continuity except the perforations B², it being understood that in this case the receptacle is filled with the washing compound through the neck B' at the time the 70 latter is unscrewed from the threaded end A' of the stick A.

In practice, two or more receptacles B are furnished with a single stick to permit use of the several receptacles for containing this 75 compound, thus using such receptacle for storing the compound. When it is desired to use the same, the operator then screws one of the receptacles in position on the stick A.

Having thus described my invention, I 80 claim as new and desire to secure by Letters Patent:

1. A clothes stick, comprising a stick having a threaded end and a perforate egg or bulb-shaped receptacle having a threaded 85 neck screwing on the threaded end of the stick and adapted to be filled with a washing compound, the said receptacle having a smooth surface throughout its entire extent to prevent injury to delicate fabrics when 90 using the clothes stick.

2. A clothes stick, comprising a stick having a threaded end, and a perforate egg or bulb-shaped receptacle provided with a 95 threaded neck adapted to screw on the said 100

threaded end of the stick, the said receptacle being provided with a screw cap to permit of opening the receptacle for filling the same with a washing compound to be dissolved in 5 the wash water, the said receptacle having a smooth surface throughout its entire extent.

In testimony whereof I have signed my

name to this specification in the presence of two subscribing witnesses.

ANNA S. TAYLOR.
